UNITED STATES PATENT OFFICE.

GEORGE D. SUTTON, OF NEW YORK, N. Y.

STREET CURB AND GUTTER.

SPECIFICATION forming part of Letters Patent No. 329,344, dated October 27, 1885.

Application filed August 29, 1885. Serial No. 175,669. (No model.)

To all whom it may concern:

Be it known that I, GEORGE D. SUTTON, a citizen of the United States, and a resident of New York, in the county of New York and 5 State of New York, have invented certain new and useful Improvements in Street Curbs and Gutters, of which the following is a specification.

My present invention relates to curbs and 10 gutters designed for the streets of cities and towns.

The object of the invention is to so construct 15 the curbs and gutters that they may be advantageously utilized as conduits for electric wires and cables, and as conduits for pipes for conveying compressed air or other motive power. By this invention I furnish a practicable method of laying the electric wires and cables beneath the surface of the ground without 20 materially interfering with the paving of the carriage-ways or sidewalks, and when put into use my system will require but slight cost for maintaining it, and, besides, it will furnish ready means of access to the wire and cable systems whenever occasion may arise for 25 repairs to the same, or for any enlargement thereof.

The features of novelty for which I desire 30 protection in this instance are pointed out in the claims at the end of this description.

In the accompanying drawings, which form 35 a part of this specification, and in which like features are indicated by like letters, Figure 1 is a cross-section of one side of a street including the gutter, curb, and sidewalk, showing the application of my invention. Fig. 2 is a cross-section of the gutter and curb, showing a modification in the shape of those features. Fig. 3 is a similar section of the 40 same parts with all the walls perpendicular. Fig. 4 is a top plan view of the cover of the curb or gutter. Fig. 5 is a similar view of the bottom of the curb or gutter, and Fig. 6 is a side view of the outer wall of the curb 45 or gutter.

In the drawings, 1 indicates the carriage-way of a street, and 2 the sidewalk. A is the hollow curb, and B the hollow gutter. These structures are entirely independent of each 50 other, as shown, so that it is practicable to use either separately, if that plan should seem

desirable. The curb A is hollow, and is designed to be of regulation size, and is preferably of cast-iron, though any other metal or substance adapted for the purpose may be 55 employed instead of cast-iron. This curb may be twenty inches deep, (more or less,) according to the requirements of the service for which it is intended, and of a width at top— say from five to eight inches, more or less— 60 sufficient to cover the surface now usually occupied by the solid stone curbs. These dimensions will of course be subject to city and town regulations, and do not enter into the merits of my invention. The curb A will 65 occupy the same relation to the carriage-way and sidewalk that the solid stone curbs now occupy, extending somewhat above the surface of the carriage-way, but being substantially on a level with the sidewalk.

In Figs. 1 and 3 the curb A is shown with 70 both of its sides perpendicular, and in Fig. 2 the inner wall is perpendicular, while the outer wall is inclined from the top to the bottom. The inclined wall of Fig. 2 gives greater 75 interior space to the curb without lessening its strength, and where the curb is used independently of the hollow gutter the inclined wall furnishes a certain amount of support for the gutter-stones, and is a safeguard against the 80 wheels of vehicles coming in violent contact with the top of the curb or with its cover. The inside of curb A may be lined with cement, or with any other suitable non-conducting substance, a. This lining may be about three- 85 eighths of an inch thick, and its object is to avoid any possibility of the metal composing the hollow curb detrimentally affecting the electric wires or cables which may be located within the same. The wires and cables will 90 of course be properly insulated, and may be provided with an armor of lead or other suitable material. When thus protected, there is little if any liability of trouble arising from induction; but the non-conductor lining serves 95 as an additional safeguard in this respect. This lining is not essential to this plan of accommodating the wires beneath the surface of the streets or roadways, and may be dispensed with in practice. The curb A is provided 100 with a top, C, which may be of the type shown, or of any other suitable type. Between the

- top C and upper edges of the curb A may be employed a gasket, *b*, of rubber or any other suitable material, for the purpose of making a perfectly-tight joint between cover and curb.
- 5 The curb may be provided with any desirable plan of supporting-brackets *h* for sustaining the wires and cables and separating groups of wires or cables from one another. The top of the curb (shown detached in Fig. 4) will, by 10 preference, be made with solid corrugated sections *c'* and corrugated removable center lid, *c*². By this construction, to which I do not confine myself, however, as the top may be in solid sections, openings are provided for 15 access to the hollow curb without the necessity of lifting the entire weight of the top C. It is of course understood that the curb A is to be made in sections of suitable length, which sections are to be connected together by any 20 practicable joint which will provide water and moisture tight connections. The bottom *c*³ of each section of the curbing will, by preference, be made in the manner shown in Fig. 5, which represents a ground plan view of the 25 bottom of one section of the curb. It will be noticed that this bottom is made with alternate solid and open sections, the letter *c*⁴ indicating the solid sections. By this construction a saving in material is effected and the curb-section 30 rendered lighter than it would be if provided with an entirely solid bottom.
- The letter B indicates a hollow gutter, which is designed to occupy the same relation to the carriage-way which the ordinary gutter occupies. It may be made with both its inner and 35 outer walls perpendicular, as shown in Fig. 3, or with both of said walls inclined outwardly, as shown in Fig. 2, or with only its outer wall inclined, as shown in Fig. 1.
- 40 When the gutter B is used in connection with the curb A, its inner wall is best made to conform to the inclination of the outer wall of the curbing; but when the gutter is used alone without the curb A, the preferred form 45 will be that shown in Fig. 1 with the inner wall perpendicular and the outer wall inclined from the top to the bottom. By this construction I provide more interior space than if the outer wall were perpendicular, and besides furnish a certain degree of support for 50 the paving-blocks at the edge of the gutter. The interior of the gutter B (which gutter is to be made in sections the same as curb A) may be lined the same as the curb A, and its 55 top and bottom may be solid, or made precisely like the top or bottom of the curb A, with the exception that the cover of the gutter will be made smooth on its exposed or outer surface. To illustrate this feature of the case, Figs. 4 60 and 5 may be deemed to show the top and bottom, respectively, of the gutter as well as the curb.
- b'* represents the gasket between the top C' and gutter B.
- 65 As already stated, the gutter may be used either with or independently of the curb. When the gutter is used without the curb A,

the sidewalk may be constructed to extend out to the gutter; or an ordinary stone curb may be interposed between the sidewalk and gutter. When the gutter B and curb A are used conjointly, they may be connected by the headed bolts *e*, provided with nuts, which may be secured against displacement by any of the commonly-employed nut-locks. To 70 accommodate the bolts *e*, the inner wall of the gutter is perforated and the outer wall of the curb is provided with elongated slits or openings *e'*. By this means the gutter can be adjusted vertically to bring it to the proper 75 position with reference to the grade of the carriage-way. It may be found necessary in order to properly secure the cover of the gutter against displacement to make use of countersunk screws or other fastening means. 80 In crossing intersecting streets the gutter-conduit B will be extended across the roadway in an obvious manner, the cover of the section or sections of that portion of the conduit being on a level with the surface of the paving 85 of the carriage-way, and being provided with corrugations on its exposed surface, as is usual with casting occupying such positions. The gutter B may be fourteen inches (more or less) in depth and from eight to twelve 90 inches wide, (more or less.) The space between the gutter and curb may be packed with any suitable water-proof substance, as indicated 95 at *c*.

I propose, in utilizing this gutter and curb, 100 to provide a bed of pebbles of several feet thickness for the structures to rest upon, thereby furnishing suitable drainage for such water as may find its way within the conduits.

One advantage of making the gutter and 105 curb of independent receptacles is that those wires or cables that are employed for very delicate service—as in telephonic or electric-light systems—may be consolidated in one receptacle, while the telegraphic and other 110 wires and cables are located in the other independent receptacle, thus avoiding an objection often made to a common conduit for the various electric-wire systems. Another advantage of this plan of independent receptacles when the arrangement shown by me is employed is that the gutter can be readily 115 adjusted to suit the grade of the carriage-way, which could not be done if the receptacles were permanently joined together.

The receptacles A and B may be provided with suitable perforations in their back walls for the purpose of making connections with the wires or pipes within the said structures and the buildings into which the electric current of compressed air or other power is to be carried for use.

Having thus described my invention, what I claim as new, and desire to secure by Letters Patent, is—

1. The hollow gutter B, combined with the hollow curb A, both receptacles being independently constructed, and connected to each other, so that the gutter may be adjusted ver-

tically with relation to the curb, substantially as set forth.

2. The hollow curb A, whose outer wall is inclined from the top to the bottom, in combination with the hollow gutter B, whose inner and outer walls are similarly inclined, the two receptacles being independently constructed and adjustably connected to each other, substantially as set forth.

10 3. The hollow curb A, having elongated slits or openings in its outer wall, in combi-

nation with the hollow gutter B, having bolt-holes in its inner wall, and the bolts e, substantially as set forth.

Signed at New York, in the county of New 15 York and State of New York, this 28th day of August, A. D. 1885.

GEO. D. SUTTON.
